DEVICE FOR USE IN THE TREATMENT OF
RAYON

Alfred E. Sunderland and Arthur L. Jackson,
Asheville, N. C., assignors to American Enka
Corporation, Enka, N. C., a corporation of Dela-
ware

Application April 20, 1940, Serial No. 330,790

3 Claims. (Cl. 91—13)

This invention relates to the treatment of yarn, thread or the like in its passage between a thread storage device and a collecting device and more particularly to treatments wherein succeeding portions of a yarn, thread or the like are passed in contact with a surface which will modify its characteristics.

While yarn or the like may be subjected to the modifying influence of many varying types of materials, liquid or solid, involving such operations as abrading, waxing, lubricating, etc., by passage across a suitably prepared surface, it will be recognized that regardless of the type of treatment to be effected it is highly desirable that the yarn or the like be modified substantially uniformly throughout its lengths.

An appreciation of typical difficulties which have been encountered in the treatment of yarns by passing the same across a prepared surface may be had by a consideration of the problems encountered in the preparation of wound cones for use in the manufacture of knitted fabrics such as underwear, tubing and hosiery. Since such cones are customarily used by the manufacturers of knitted goods in the form in which they are received from the yarn producers, it is encumbered upon the latter to furnish the cones in a condition suitable for insertion directly into knitting machinery without further alteration. It has been found that yarns for use in such machinery must be suitably lubricated in order to render them sufficiently flexible and pliable to be fed through knitting needles without danger of breakage. Furthermore, the good appearance of the knitted fabric is to a large extent dependent upon the amount of lubricant accepted by the yarn and the evenness of its distribution over succeeding portions thereof. In furnishing yarns to be used in knitting operations, it is necessary therefore that the entire length of yarn be uniformly lubricated to an extent within critical limits so that the knitting operation may progress efficiently while the finished product will have a commercially desirable appearance and feel.

In lubricating yarns for use in knitting machinery and the like, it is now the common practice to apply the lubricant during that winding operation in which cones are prepared for shipment. Usually the yarn is passed from a supply package tangentially across a cylindrical metal roller which rotates partially submerged in a suitable lubricant bath, generally formed of an oil, to a driven collecting bobbin or the like. The roller is so arranged with respect to the lubricant

bath as to pick up a film of lubricant of sufficient thickness to permit the imparting of a definite amount thereof to the yarn passing thereover, the amount in any instance, of course, being dependent upon the size or denier of the yarn being wound, as well as the use to which the yarn is to be put. The roller is driven at a constant speed and turns in a direction contrary to or in the direction of the yarn travel, thus continuously presenting a uniformly coated surface to the yarn.

As has been pointed out above, it is highly desirable not only that a suitable amount of lubricant be imparted to a given length of yarn but also that such amount be applied uniformly for the entire length of the yarn. This is difficult of accomplishment by the employment of conventional machinery because of the fact that the speed of yarn take-up steadily increases as the driven cone increases in diameter while the roller is driven at a constant speed so that the time of contact of the yarn with the roller proportionally decreases as the winding operation progresses. An attempt has been made to obviate this difficulty by the use of a device for progressively guiding the yarn across the roller at an increasing angle as the cone diameter increases, thus compensating for loss of contact time by the provision of a longer and wider path of contact. Another method of providing for increased delivery of lubricant to compensate for increased speed of take-up, is to regulate the thickness of the lubricant film on the roller by means of a scraper. The distance between the scraper and oiling roller is gradually increased in proportion to increase in take-up speed thereby causing the yarn to contact a thicker lubricant film near the end of the winding operation.

While the use of the devices outlined above has resulted in some improvement with respect to the maintenance of uniformity of application of lubricant to succeeding portions of yarn, it has been noted that the amount of lubricant accepted by the yarn during that period when the cone is being started and consequently its take-up is near the minimum is generally higher than the desired amount and that at this stage the application of lubricant to succeeding portions of yarn lacks uniformity. By experiment, it was determined that the initial non-uniformity and excess lubrication of the yarn results from vibration thereof in its path over this lubricating roller. The vibration causes the surface contact between the yarn and roller to vary considerably with the result that the amount of lubricant accepted by the yarn under these con-

ditions is in excess of that desired and less uniformly distributed. It was further discovered that the extent and duration of the vibration is subject to considerable variation when yarns of differing deniers or other physical characteristics are being wound. On the other hand, later, during the winding operation, when the angular travel of the thread causes the thread to press against the side of the front thread guide the vibration is stopped and satisfactory lubrication can be effected. This time, of course, will depend upon the characteristics of the yarn, the winding speed and other variables.

Inasmuch as it was found that satisfactory lubrication is possible during the latter part of the winding operation as described above, it was thought desirable to place a tensioning device in the path of the yarn adjacent the lubricant roller and to provide means for causing this tensioning device to have a braking action during the initial winding of the cone while the braking action could be automatically released whenever the peripheral speed of the cone became sufficient to produce satisfactory tensioning of the yarn. Devices of this character were found to be disadvantageous in that constant adjustment of the tension releasing mechanism is necessary and the initial installations are quite costly.

It is an object of this invention to overcome all of the difficulties heretofore encountered in the treatment of yarn by the passage by the same across a surface which will modify the characteristics thereof and to produce a surface treated yarn which is modified uniformly throughout its length.

By the employment of this invention, it is contemplated that yarn treated by contact with a modifying surface during a winding operation will be automatically maintained in proper relation to such surface regardless of the speed of travel of the yarn.

It is further contemplated by the use of this invention to damp the vibrations of yarn or the like being drawn between a storage device and a treating surface in such a way that increased tensioning of the yarn is avoided, while uniform treatment of succeeding portions thereof is made possible. Uneven and excessive tensions incident to drag between the yarn and treating surface are entirely eliminated while mechanical tensioning of the yarn during the initial winding stages with its concomitant difficulties of adjustment is rendered unnecessary.

According to this invention, vibrations of yarn or the like being drawn between a storage device and a treating surface will be effectively damped, regardless of the take-up speed, the angle of approach to the lubricating roller, or the physical characteristics of the yarn being wound.

Further objects and advantages of the present invention will be apparent from a consideration of the following detailed description of a preferred embodiment thereof taken in conjunction with the annexed drawing wherein:

Figure 1 is a view in front elevation of a portion of a winding machine showing a preferred form of the vibration damping device of the present invention in damping position;

Figure 2 is a view in section taken along the line 2-2 of Figure 1;

Figure 3 is a detail view in side elevation of the preferred form of damping device shown in Figures 1 and 2;

Figure 4 is an end view of the damping device;

Figure 5 is a top plan view of the damping device; and

Figure 6 is a bottom plan view of the damping device.

Referring to the drawing in further detail, the invention is shown in a machine adapted to receive yarns or the like 10 from some source, not shown, which may be a spool, cake or the like, which yarns are to be treated with a liquid dressing such as a lubricating oil or emulsion and are to be wound into the form of cones or cops. Inasmuch as the machine is adapted to simultaneously treat and wind a plurality of yarns by identical mechanism, the description will be confined for convenience to the mechanism acting upon a single yarn. It is understood, however, that any number of such mechanisms may be included in the machine and may be operated simultaneously.

Thread 10, taken from its source, is passed through a stationary pigtail guide 11, through damping device 12, tangentially across a roller 13, through an additional pigtail guide 14 and a tensioning device 15, of well known form, to a traverse mechanism 16 through which it is drawn by cone or cop 17 mounted for rotation on a shaft 18 driven at constant speed from a source of power not shown.

Roller 13, across which thread 10 passes in its travel between the source and cop 17, is mounted for rotation with shaft 19 which is driven from a source of power not shown. Shaft 19 is so journaled that roller 13 will rotate partially below the edge of longitudinally extending tank or trough 20 which is partially filled with a suitable lubricating oil or emulsion 21. By way of convenience, the front wall of trough 20 constitutes a support for pigtail guide 11 and damping device 12.

Guide 14 is attached to a sleeve 22 which is axially movable along a shaft 23, this movement controlling the path of yarn 10 across roller 13. The movement of sleeve 22 is effected automatically so that the length and width of the path of the yarn in contact with the roller is increased as the speed of take-up increases due to increase in effective diameter of the cop 17. There are several excellent known mechanisms for effecting this automatic adjustment and since such adjustment is not a part of this invention further reference thereto is deemed unnecessary.

Traverse mechanism 16 is of conventional form and includes a guide member for causing the yarn to be wound on the cop in a series of helices. The guide member is mounted on a cone surface contacting member 24 which in turn is arranged for pivotal movement about shaft 25 in response to variations in the effective diameter of the cop. One of the many well known means for maintaining member 24 in contact with the body of wound yarn is employed.

The damping device 12 which is interposed in the path of the yarn 10 between pigtail guide 11 and the lubricating roller 13 is illustrated in detail in Figures 3 to 6, inclusive. It consists of two sections 26 and 27 fastened together by a bolt 28 and a nut 29. Depending from the section 27 is a threaded shank 30 which is screwed into the front of trough 20 as is illustrated in Figure 2. Section 27 is also provided with an arcuate guide piece 31 which extends downwardly toward the yarn source below pigtail guide 11. The inner surface of sections 26 and 27 are designed to present a series of interdigitating corrugations 32 which define a tortuous path of

multiple contact points situated on each side of the thread travel. The corrugated surfaces of sections 26 and 27 are so arranged that when the two sections are assembled the width of the path defined between said surfaces at any point will be constant. In other words, the corrugated surfaces are parallel as can be clearly seen in Figure 4. As will be seen by consulting Figure 1, the thread is passed under the arcuate guide piece 31 and between the corrugations 32 of sections 26 and 27, across the roller 13 to the pigtail guide 14. It should be borne in mind that device 12 is not a tensioning member and consequently the thread passing therethrough need have only enough contact therewith to damp vibrations. For this reason, section 27 is provided with a shoulder 33 against which section 26 bears when held in position by bolt 28. Shoulder 33 is of such a height that the corrugations 32 on sections 26 and 27 are spaced apart about 1 mm. when the said sections are held in operative position. To render the width of the tortuous passageway adjustable, a washer 34 may interpose between sections 26 and 27 on the bolt 28. By inserting washers of various thicknesses the width of the corrugated passageway may be varied as desired. It is of importance, however, that sections 26 and 27 be far enough apart so that no material tensioning of the yarn passing therethrough will result, regardless of the denier or other physical characteristics thereof.

Shoulder 33a and guide piece 31 coact to keep yarn 10 within the confines of the spaced apart corrugations against radial movement in a direction parallel to the longitudinal axis of the device 12. Thus, the vibrations of yarn 10 prior to the action of damping device 12 thereon cannot, because of shoulder 33a and guide piece 31, cause the yarn to move out from the path between sections 26 and 27.

When the device is to be put in operation, it is threaded up by passing yarn from the storage device through guide 11, under arcuate guide piece 31, between members 26 and 27, tangentially across roller 13, through pigtail guide 14, tensioning device 15 and traverse mechanism 16, to the cop or cone 17 to which the end is attached. Cop 17 is then driven through a shaft 18 and the winding operation is commenced. When cop 17 is drawing yarn 10 from its source through the various guides, shaft 19 and roller 13 are caused to rotate in a direction counter to or in the direction of the path of travel of the yarn. Thus, lubricant 21 is picked up by the roller and imparted to the yarn at the point of tangential contact. Because of the damping effect of device 12, the yarn will not vibrate between damping device 12 and roller 13 at any time during the winding operation and the coating of the yarn will be quite uniform.

By experiment it was found that the following oil percentages are yielded by a thread of 150 denier being passed through a device of the type shown in Figure 1 employing movable sleeve 22 but using an ordinary pigtail guide in lieu of damping device 12:

Status of winding	Oil
	Percent
Start.....	10.0
After 11,000 yds.....	7.0
After 22,000 yds.....	5.8
After 33,000 yds.....	5.5

On the other hand, when the damping device of this invention was used, all other conditions being the same as above set forth, the following oil percentages were yielded:

5	Status of winding	Oil
	Percent	
Start.....	4.2	
After 11,000 yds.....	4.3	
After 22,000 yds.....	4.0	
After 33,000 yds.....	4.3	

15 The above results were attained without any adjustment whatsoever of the damping device 12 after the initial adjustment prior to starting the winding operation. By these experiments it is clearly shown that device 12 does not act as a tensioning device, for, if it did, the tension which it imparts to the thread, coupled with the increase in tension resulting from increased peripheral speed of cone 17, would cause a decreased take-up of lubricant near the end of the winding period.

20 I will be apparent that the width of the tortuous path defined between interdigitating members 32 may be adjusted to accommodate yarns and threads having different deniers or other physical characteristics.

25 The above description of a preferred embodiment of this invention is but for purposes of illustration and it is not intended that the scope of the invention be limited beyond the spirit of the appended claims.

30 What is claimed is:

35 1. In a treating machine wherein yarn, thread or the like is collected in package form, in combination, a source of yarn, means for contacting said yarn with a treating surface, and means presenting a fixed corrugated surface having multiple points of contact on each side of the path of travel of the yarn intermediate said source and treating surface, said corrugated surfaces being in parallel spaced relationship and the opposed multiple points of contact thereof being spaced substantially 1 mm. apart.

40 2. In a treating machine wherein yarn, thread or the like is collected in package form, in combination, a source of yarn, means for contacting said yarn with a treating surface, means presenting a fixed corrugated surface on each side of the path of travel of the yarn intermediate said source and said treating surface, said surfaces being parallel to present opposed multiple points of contact to the yarn passing therebetween, said opposed multiple points of contact being spaced at a distance greater than the diameter of the yarn and means associated with said holding means for adjustably determining the distance between said surfaces.

45 3. In a treating machine wherein yarn, thread or the like is collected in package form, in combination, a source of yarn, thread or the like, means for contacting said yarn with a treating surface and means presenting a fixed corrugated surface on each side of the path of travel of the yarn intermediate said source and said treating surface, said corrugated surfaces being in parallel spaced relationship and presenting opposed multiple, relatively sharp-edged points of contact to the yarn passing therebetween, said opposed multiple points of contact being spaced substantially 1 mm. apart.

50 ALFRED E. SUNDERLAND,
ARTHUR L. JACKSON.
